UNITED STATES PATENT OFFICE.

BERNARD A. BEHREND, OF NORWOOD, OHIO, ASSIGNOR TO ALlis-CHALMERS COMPANY, A CORPORATION OF NEW JERSEY, AND THE BULLOCK ELECTRIC MANUFACTURING COMPANY, A CORPORATION OF OHIO.

ROTOR CONSTRUCTION.

No. 921,505.

Specification of Letters Patent.

Patented May 11, 1909.

Application filed June 25, 1906. Serial No. 323,225.

To all whom it may concern:

Be it known that I, BERNARD A. BEHREND, a citizen of the United States, residing at Norwood, in the county of Hamilton and State of Ohio, have invented certain new and useful Improvements in Rotor Construction, of which the following is a full, clear, and exact specification.

My invention relates to the rotary members of dynamo-electric machines and particularly to the rotary field members of turbo-alternators.

One of the objects of my invention is to provide a rotary member for high speed machines which is strong, compact and consists of few parts all of which are well protected against displacement by centrifugal force,

A further object is to provide an improved and simplified means for supporting, adjusting and retaining in position the end-turns of the coils.

A still further object is to provide a solid core construction having air passageways so arranged that there is no danger of an excessive rise in temperature.

My invention consists in the details of construction and in the combinations and arrangements of parts described in the specification and set forth in the appended claims.

For a better understanding of my invention, reference is had to the accompanying drawings in which—

Figure 1 is a partial sectional elevation of a rotary field member constructed according to my invention; Fig. 2 is an end elevation with parts broken away, and the shaft in section; Fig. 3 is an elevation of a portion of the core and shaft; and Fig. 4 is a partial end view of the adjustable wedges which support the end-turns of the field coils.

Referring now to the figures of the drawings, I have shown at 10 a rotary member which is in this case a rotary field member of a turbo-alternator. The core 11 of the rotary member is solid and provided with integral shaft projections, one of which is shown at 12. The core and shaft projections are preferably made from a single steel forging. The shaft projections adjacent the core are inclined or tapered as shown at 13 for purposes to be explained. The core is provided with radial slots 14 for the reception of field coils and with solid pole pieces 15, a four pole rotor being here shown. The

pole pieces are in this case separated by six 55 radial coil slots, there being three coils per pole. In Fig. 1 the end-turns of three of these coils are shown at 16. The ends of the teeth are provided with slots 17 for the reception of non-magnetic coil retaining wedges. 60 Each pole piece is provided at the end with a ventilating slot 18, extending from the periphery inward toward the shaft.

At 19 is shown an end cover for the end-turns of the field coils, consisting of a ring or 65 shield 20 surrounding the coils and an integral inwardly extending portion 21 at right angles to the ring 20. The edge of the ring 20 nearest the field core engages and fits closely within a groove 22 at the edge of said 70 core. The end-turns are supported by coil seats 23 which in this case are wedges or blocks provided with inclined inner surfaces resting upon the inclined portions 13 of the core or shaft projections. As many of these 75 wedges can be employed as is necessary. These coil seats or supports are each provided with an inclined inner portion 23^a which engages the inclined portion of a shaft projection, and with a shorter portion 24 80 which bears against the coils. When these coil supports are arranged end to end, the spaces between the portions 24 permit a circulation of air as will be explained. The outer ends of the coil seats or supports are 85 notched or cut away to receive an adjusting nut 25 engaging the threaded portion 26 of the shaft. Thus it is seen that by merely turning the nut 25 the position of the coil seats or supports can be changed, thereby 90 adjusting the outward pressure of the coils on the end rings or cover.

The inner edge of the inwardly extending portion 21 of the end cover is notched as shown at 27, and engages the radial arms 28 95 of the member 29 on the shaft, the arms being provided with shoulders which engage the notch 27 in the end cover, forming a rabbet joint. The spaces between the arms 28 form openings for air currents, which, 100 when the rotor is in operation, pass inward along the shaft projections, under the end-turns of the coils and out through the openings or slots 18 in the ends of the field poles. At 30 is shown an adjusting nut for the 105 member 28 and end cover 19, which nut engages a threaded portion 31 of the shaft. By adjusting the position of the nut 31, mem-

ber 29 and end cover 19 can be moved toward or away from the core for adjusting the end-turns in an axial direction. The end-turns are preferably spaced apart and 5 from the portion 21 of the end cover and from the core by blocks of insulation 32.

It is seen that the rotary member is very compact and strong and consists of fewer parts than the previous constructions of 10 similar types of machines. The end-turns of the coils can be adjusted outwardly against each end cover by means of the wedge-shaped coil seats and adjusting nut 24, and in an axial direction by means of 15 the adjusting nut 30 and end covers 19. When the rotary member is in operation, a large volume of air is drawn through the spaces between the radial arm 28 of the member 29, under the end-turns of the coil 20 between the coil seats, and out through the slots 18 in the ends of the field poles. An excessive rise of temperature is thus prevented.

I do not wish to be confined to the exact 25 details shown as many modifications can be made without departing from the spirit and scope of my invention, and I aim in my claims to cover all such modifications.

What I claim as new and desire to secure 30 by Letters Patent is:—

1. In a rotary field member for dynamo-electric machines, a solid cylindrical core having shaft projections integral therewith, said core having slots for the reception of 35 field coils, coils in said slots having end-turns, end rings surrounding the end-turns, adjustable seats or supports for the end-turns resting directly upon the shaft projections and adjustable outwardly to force 40 the end-turns against the surrounding end rings, and means for adjusting said seats or supports.

2. In a rotary field member for dynamo-electric machines, a solid cylindrical core 45 having integral shaft projections, said core having slots for the reception of field coils, field coils in said slots, end rings surrounding the end-turns of said coils, wedge-shaped coil seats or supports for said coils resting 50 directly on the shaft projections, and means for adjusting the coil seats or supports to adjust the outward pressure of the coils on the rings.

3. In a rotary member for dynamo-electric machines, a slotted core having integral inclined or tapered portions at the ends thereof, coils in the slots of the core, said coils having end-turns extending beyond the slots of the core, end rings surrounding 60 the end-turns, wedges or blocks having inclined faces resting on said inclined portions and supporting the end-turns, and means for adjusting the wedges or blocks for adjusting the outward pressure of the coils on the 65 end rings.

4. In a rotary member for dynamo-electric machines, a solid slotted core having integral inclined or tapered shaft projections, coils in the slots, wedges or blocks having inclined faces resting on said inclined projections and supporting the coils, and end rings surrounding the end-turns. 70

5. In a rotary member for dynamo-electric machines, a solid slotted core having integral inclined or tapered shaft projections, coils in 75 the slots, coil seats or supports resting on the inclined or tapered portions, end rings surrounding the end-turns, and means for changing the positions of the coil seats or supports to adjust the pressure of the end-turns on 80 the end rings.

6. In a rotary member for dynamo-electric machines, a slotted core and shaft projections all in one integral mass, the projections at the ends of the core being inclined or 85 tapered, coils in the slots of the core, coil supports or seats having inclined faces resting on the inclined portions of the shaft projections, end rings surrounding the end-turns, and means for adjusting the positions of the coil 90 seats or supports to adjust the pressure of the coils on the end rings.

7. In a rotary field member for dynamo-electric machines, a cylindrical core body having radial slots for field coils and solid 95 pole pieces, the ends of the poles being slotted for the passage of air.

8. In a rotary field member for dynamo-electric machines, a solid cylindrical core body having slots for the field coils and solid field 100 poles, field coils in the slots of the core, the poles at the ends thereof having slots extending from the outer surface to the shaft whereby air can pass axially under the end-turns and outward between the latter and the 105 poles, through said slots.

9. In a rotary field member for dynamo-electric machines, a solid cylindrical core having integral shaft projections, said core having field poles, and slots for the reception 110 of field coils, coils in said slots, end rings surrounding the end-turns, and seats or supports for the end-turns of the coils resting directly on the shaft projections, the ends of the poles being slotted whereby air can pass 115 from an axial direction between the seats or supports and outward through the slots in the core.

10. In a dynamo-electric machine, a cylindrical core having coil slots, field coils in 120 said slots having end-turns or projections, end covers for the end-turns of the coils, each end cover comprising a ring or shield surrounding the end-turns and an integral plate extending inwardly toward the shaft, and a 125 member on the shaft having radial arms forming a seat for said inwardly extending plate.

11. In a dynamo-electric machine, a cylindrical core having coil slots, field coils in said 130

- slots and having end-turns or projections, end covers for the end-turns of the coils, each end cover comprising a ring or shield surrounding the end-turns and engaging the 5 end of the core, and an integral portion extending inwardly toward the shaft, and a member on said shaft having radial arms engaged by said inwardly extending portion.
12. In a dynamo-electric machine, a cylindrical core having coil slots, field coils in said slots having end-turns or projections, and covers for the end-turns of the coils, each end cover comprising a ring or shield surrounding the end-turns, and a portion extending inwardly toward the shaft, a member on said shaft having radial arms on which said inwardly extending portion rests, and means for adjusting the position of said member on the shaft for forcing the end 15 covers inward toward the core.
13. In a dynamo-electric machine, a cylindrical core having coil slots, field coils in said slots and having end-turns or projections, end covers for the end-turns of the coils, each end cover comprising a ring or shield surrounding the end-turns and engaging the end of the core, and an integral portion extending inwardly toward the shaft, a member on said shaft having radial arms engaged by said inwardly extending portion, and means 20 for adjusting the position of said member on the shaft for moving the end cover inwardly toward the core.

In testimony whereof I affix my signature, in the presence of two witnesses.
